UNITED STATES PATENT OFFICE.

DAVID DARWIN, OF IRON RIVER, WISCONSIN.

GRAIN-DOOR.

1,068,327.

Specification of Letters Patent.

Patented July 22, 1913.

Application filed July 22, 1911, Serial No. 899,943. Renewed January 17, 1913. Serial No. 742,745.

To all whom it may concern:

Be it known that I, DAVID DARWIN, a citizen of the United States, residing at Iron River, in the county of Bayfield and State 5 of Wisconsin, have invented new and useful Improvements in Grain-Doors, of which the following is a specification.

The present invention provides a door for closing the opening in the side of a box car 10 designed chiefly for hauling grain, fertilizer and like commodity in bulk, the purpose being the provision of a door which may be readily moved aside when it is required to unload the car, thereby avoiding the common practice of destroying grain doors when 15 unloading the grain.

The invention contemplates a sectional door, novel mountings therefor and protective means for preventing injury to the door 20 jambs, said protective means supporting antifriction rollers which enable the door to be easily moved.

The invention consists of the novel features, details of construction and combination 25 of parts, which hereinafter will be more particularly set forth, illustrated in the accompanying drawings, and pointed out in the appended claims.

Referring to the drawings, forming a part 30 of the specification, Figure 1 is a transverse section of a grain car provided with grain doors embodying the invention, the full lines showing the doors in position for closing the door openings and the dotted lines indicating the position of the doors when elevated 35 or moved out of the way. Fig. 2 is a horizontal section. Fig. 3 is a view of the grain door as seen from the inner side, showing a portion of a side of the car, parts being broken away. Fig. 4 is a vertical section of 40 the door. Fig. 5 is a view of one of the sections of the door. Fig. 6 is a horizontal section of a modification. Fig. 7 is a detail section on the line 7—7 of Fig. 6, looking in the direction of the arrows. Fig. 8 is a sectional 45 detail on the line 8—8 of Fig. 6, looking to the right, as indicated by the arrows. Fig. 9 is a horizontal section of a further modification.

Corresponding and like parts are referred 50 to in the following description, and indicated in all the views of the drawings, by the same reference characters.

Guides 1 of substantially U form in cross 55 section extend along opposite sides of the door openings and across the top of the car.

The open sides of the guides face inward toward the door opening and the vertical portions of said guides are attached to the inner faces of the door jambs 9. The upper portions of the guides extending beneath the roof of the car overlap, thereby admitting of the doors when moved out of the way occupying a position one above the other. A depression or drop 13 is formed in the guides 60 at the angle between the vertical and horizontal portions for the purpose of engaging the projections of the doors to hold the latter suspended. The guides 1 preferably consist of metal bars which may be formed in any 65 manner.

Each of the doors comprises similar sections 3 and 3^a, each of the sections consisting of sheet metal of suitable length and width. Portions are pressed from the sections of the door to form ribs for stiffening and strengthening the same. The ends of the door sections are bent laterally, as indicated at 4, and operate in slots 10 formed in the inner sides of the door jambs, thereby preventing waste 75 of grain or other commodity stored in the car. End portions of the door sections are left plain, as indicated at 5, to ride upon the antifriction wheels 7 located in the door jambs and designed to relieve friction and 80 cause the doors to slide freely in their vertical movements. The door sections are strengthened at their upper and lower edges by rods 2, which are fitted thereto, being preferably inserted in rolls formed by bending 85 edge portions of the sheet metal plates. The rods project a short distance beyond the flanged ends of the door sections to enter the guides 1. A curved flange 12 is formed at the lower edge of the upper door section 3 to 90 engage over the upper rod provided at the upper edge of the lower door section to insure the formation of a tight joint between the two sections when lowered to close the door opening.

Each door jam is protected by means of a plate 6 of L-form, one wing of the plate covering the side of the door jamb facing the door opening and the other wing protecting the side of the door jamb facing the 105 interior of the car. Openings are formed at intervals in the wing of the protective plate facing the interior of the car to admit of portions of the antifriction wheels 7 projecting to engage end portions of the doors. 110 Brackets or strap 8 assist in supporting the antifriction wheels 7 and are attached to

the wings of the protective plates 6. A guard 11 protects the guide and consists of a metal strip bent into substantially an ogee form between its longitudinal edges, one edge of the guard being secured to the guide and the other edge being attached to the inner face or wall of the side of the car. A catch 14 is provided upon each door jamb and is adapted to engage over the doors to hold the same in closed position. The catches have both pivotal and adjustable connection with the door jambs and are longitudinally slotted to receive the pivot fastenings.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the embodiment thereof, I desire to have it understood that the device shown is merely illustrative, and that such changes may be made when desired as are within the scope of the claims appended hereto.

Figs. 6, 7 and 8 show a modified form of catch which is mounted to receive both a pivotal and a sliding movement. The catch B is pivoted to a slide A which is mounted on the door jamb to move vertically. A spring C of the contractile type normally exerts a downward pull upon the slide A to hold the catch B in engagement with the rod 2. The slide A is mounted within the door jamb and has a projecting portion to which the catch B is pivoted. In the event of the door jamb being of wood the latter is cut away upon a side to receive the slide A and the protector 6 has a slot in which the projecting portion of the slide is arranged to operate.

Fig. 9 shows a modification in which the door jamb is formed as a part of a side of the car, particularly when the latter is constructed of plate steel. In this case the antifriction wheels 7 are mounted directly upon the door jamb, portions of the latter

having openings to admit of the antifriction wheels projecting so as to come in contact with the door.

Having thus described the invention what is claimed as new, is:—

1. In a grain car having jambs at opposite sides of the door opening and having the sides of said jambs facing the door opening and the interior of the car covered by means of plates, said jambs being further provided upon their inner sides with grooves, U shaped guides secured to the inner faces of the jambs, a sheet metal door having its vertical edge portions bent to provide flanges arranged to operate in the grooves formed in the inner faces of the door jambs, and rods secured to the upper and lower ends of the door and projecting beyond the flanged edges thereof to enter the said U shaped guides.

2. In a grain car having jambs at opposite sides of the door opening, protecting strips of metal covering the sides of said jambs facing the door opening and the interior of the car, antifriction wheels mounted upon the protecting strips and having portions extending beyond the flanges of said strips facing the interior of the car, and a sliding door mounted to move upon said jambs.

3. In a grain car having jambs at opposite sides of the door opening, metal guides of U form secured to the inner sides of said jambs, protecting strips of metal covering the sides of said jambs facing the door opening, antifriction wheels mounted upon the protecting strips, a door slidably mounted in the guides and adapted to engage the antifriction wheels, and guards consisting of metal strips bent between their longitudinal edges and having an edge portion of each secured to one of the guides and having the opposite edge portion attached to the inner side of the car.

In testimony whereof I affix my signature in presence of two witnesses.

DAVID DARWIN.
